CARTON PACKING FIXTURE

John K. Wickliffe, Chicago, Ill., assignor to Industrial Patents Corporation, Chicago, Ill., a corporation of Delaware

Application December 19, 1936, Serial No. 116,841

3 Claims. (Cl. 226—129)

This invention relates to a packing fixture.

One of the objects of the invention is to provide an improved packing fixture.

Another object of the invention is to provide a device for facilitating the packing of ordinary articles of commerce.

Other objects of the invention will be apparent from the description and claims which follow.

The device of the present invention is adapted for packaging numerous articles of commerce, but by way of illustration and not by way of limitation will be described for use in packing link sausage.

In accordance with the present invention, there is provided a single rack means having individual compartments for carrying a working supply of wrapping elements within convenient reach of an operator. The device of the present invention also provides means for supporting a supply of product and for conveniently supporting a partially formed carton during packing thereof.

Reference is had to the drawing in which like characters of reference are used to designate similar elements.

Figure 1 is a perspective view of a packing fixture constructed in accordance with the present invention.

Figure 2 is a plan view of the device shown in Figure 1.

Figure 3 is a sectional view taken on line 3—3 of Figure 2.

The packing fixture illustrated in the drawing comprises a bottom 1, rear wall 2 and side walls 3. Side walls 3 are cut away, as on lines 4 and 5, and, at their forward ends, are inclined toward bottom 1 as at 6, for the support of inclined packing base 7. Packing base 7, at its forward edge, is provided with retaining ledge 8 for maintaining cartons 9 on base 7 during packing thereof.

In practice, bottom 10 and rear wall 11 of carton 9 are respectively secured against base 7 and ledge 8 for packing, as shown in Figure 3. Ledge 8 is secured at substantially a right angle to base 7, and, at its end edges 12 is provided with resilient clamps 13 secured as by screws 14. Clamps 13 extend rearwardly from ledge 8 in substantially parallel relation with base 7 and serve to suitably support side walls 15 of carton 9 while being packed. As shown in Figure 2, clamps 13 are suitably flared at their free ends 16 to facilitate insertion of the carton therebetween. Ledge 8 may be cut away as at 17 to facilitate removal of the packed carton from base 7.

As shown in Figure 3, bottom 1 is curved up-

wardly as at 18 and rigidly secured to the rearward edge of base 7 as at 19, thus providing compartment 20 for retaining a working supply of carton inner liners 21.

Compartment 22 comprising bottom 23, front wall 24, rear wall 25 and side walls 26, is rigidly secured at its front wall 24 against edges 4 of side walls 3 and thus serves to carry a working supply of dividers 27 of cardboard or other suitable material.

Substantially rectangular platform 28 serves to support tray 29 containing product such as links of sausage or other product for packing in carton 9. Platform 28 is rigidly secured at its forward edge 31 to rear wall 25 of compartment 22 and, at its rearward edge 32, is rigidly supported by standard 33 bolted or otherwise secured as at 34 to flange 35, integral with wall 2, and to platform 28 at 30.

It will be noted that rear wall 25 of compartment 22 extends slightly above the platform 28 to provide retaining shoulder 36 for tray 29.

Compartments 20 and 22 and platform 28 are respectively arranged rearwardly of packing base 7 and preferably in inclined relationship with 25 packing base 7. This relationship of the several members serves to facilitate handling of the several elements contained therein.

The packing fixture of the present invention may be rested on a table or other supporting means, not shown, upon which may be stacked a working supply of carton blanks for forming cartons 9. In practice, the operator faces the fixture with ledge 8 positioned immediately in front of him. As shown in Figure 3, a carton 9 is formed as by securing rear wall 11 and side walls 15 and positioned ready for packing, that is, bottom 10 is placed adjacent packing base 7, rear wall 11 adjacent retaining ledge 8 and side walls 15 between clamps 13.

The product may be packed in carton 9 in any suitable manner. In practice, a liner 21 is drawn from compartment 20 and suitably placed within the carton. A quantity of product is then transferred from tray 29 to carton 9 sufficient to provide a single layer. A divider 27 is then taken from compartment 22 and placed over the layer of packed product whence product sufficient to provide a second layer is taken from tray 29 and packed above divider 27. The loose ends of liner 21 are then folded above the packed product and carton 9 closed thereon. The packed carton is then removed from the fixture ready for shipping or for packing in an outer shipping container.

It will be seen that the device of the present invention provides a compact form for packing product in ordinary cartons of commerce and for retaining in convenient order a working supply of wrapping elements used therein, thereby providing a considerable saving in time and labor.

I claim:

1. In a packing fixture including a bottom, a rear wall, and side walls extended forwardly of the bottom, the side walls at their top edges being inclined downwardly toward their forward end edges, a carton supporting base provided with a carton retaining ledge fixedly secured between the side walls and adjacent the forward ends thereof, a resilient clamp extending from each of the end edges of the carton retaining ledge and in substantially parallel relationship with the carton supporting base for securing a carton relative to the base and ledge, an opening between the side walls and to the rear of the carton supporting base providing a carton liner retaining compartment, the carton liner retaining compartment being extended adjacent the bottom rearwardly to the rear wall, a carton divider compartment secured rearwardly of the opening and above the carton liner retaining compartment as it extends adjacent the bottom, and a product supporting platform secured rearwardly of the carton divider compartment.
2. In a packing fixture including a bottom, a rear wall, and side walls extended forwardly of the bottom, the side walls at their top edges being inclined downwardly toward their forward end edges, a carton supporting base provided with a carton retaining ledge fixedly secured between the side walls and adjacent the forward ends

thereof, a resilient clamp extending from each of the end edges of the carton retaining ledge and in substantially parallel relationship with the carton supporting base for securing a carton relative to the base and ledge, an opening between the side walls and to the rear of the carton supporting base providing a carton liner retaining compartment, the carton liner retaining compartment being extended adjacent the bottom rearwardly to the rear wall, a carton divider compartment secured rearwardly of the opening and above the carton liner retaining compartment as it extends adjacent the bottom, and a product supporting platform secured rearwardly of the carton divider compartment, the carton liner compartment opening, the carton divider compartment, and the product supporting platform each being provided in inclined relationship with the packing base.

3. In a packing fixture including a bottom and side and rear walls, the side walls at their top edges being inclined downwardly toward their forward end edges, a carton supporting base provided with a carton retaining ledge fixedly secured to the inclined edges of the side walls and at the forward ends thereof, a resilient clamp extending from each of the end edges of the carton retaining ledge and in substantially parallel relationship with the carton supporting base for securing a carton relative to the base and ledge and an opening between the side walls and to the rear of the carton supporting base providing a carton liner retaining compartment, the carton liner retaining compartment being extended adjacent the bottom rearwardly to the rear wall.

JOHN K. WICKLIFFE.
